UNITED STATES PATENT OFFICE.

THOMAS B. CAMPBELL, JR., OF PITTSBURGH, PENNSYLVANIA.

BREAKING AND TRANSFERRING MECHANISM FOR SHEET-GLASS-DRAWING MACHINES.

Application filed April 11, 1923. Serial No. 631,330.

To all whom it may concern:

Be it known that I, THOMAS B. CAMPBELL, Jr., a citizen of the United States, and a resident of Pittsburgh, in the county of Allegheny and State of Pennsylvania, have invented a new and useful Improvement in Breaking and Transferring Mechanism for Sheet-Glass-Drawing Machines, of which the following is a specification:

10 This invention relates to glass drawing apparatus, and particularly to a breaking and transferring mechanism for use in connection with a sheet-glass drawing device.

15 It is a general object of the invention to provide a combined breaking and transferring mechanism of the type referred to which is simple and durable in construction, which contains a minimum number of parts, which is free of parts which will readily 20 get out of order, and which is highly efficient in operation.

It is a special object to provide a breaking and transferring mechanism in which all of the parts constantly move in a single 25 predetermined direction, and in which all of said parts partake of a rotary or circular motion in contra-distinction to a reciprocating or oscillating one for the purpose of avoiding abrupt changes in the direction 30 of travel and lending to the smoothness of operation.

It is another special object to provide a 35 breaking and transferring mechanism in which the arms of the rotary carrier, for receiving the several severed sections or panes and depositing the same upon the conveyor, terminate in close proximity to the normal vertical path of travel of the drawn sheet, and in which the said arms 40 may be freely projected between the several sections comprising the conveyor for delivering the severed sheets or panes to the leers.

Other special objects are to provide a 45 mechanism of the character referred to which can be easily adjusted to accommodate sheets of varying thickness and of different lengths, one in which the severed sections will be gently lifted and deposited 50 upon the conveyors for transfer to the leers, in which the entire operation is automatic, and which can be readily applied to sheet glass drawing machines already in use.

These and other objects of the invention 55 will more fully appear when taken in con-

nnection with the following description and the appended claims.

In the accompanying drawings Fig. 1 is a plan view of the preferred embodiment of the invention; Fig. 2 a side elevation of the 60 mechanism illustrated in Fig. 1; Fig. 3 a vertical sectional view taken substantially on the line III—III of Fig. 1, illustrating the parts in the positions which they assume when the breaking off cam is in its inoperative position; and Fig. 4 a view similar to Fig. 3 showing the relative positions which the parts assume when the breaking off cam has reached its operative position, and illustrating the method of transferring the 70 severed sections or panes onto the rotating carrier.

The present invention has been particularly designed for use in connection with sheet-glass drawing machines in which the 75 sheet of formed glass is constantly drawn upwardly in a vertical path, for instance in an apparatus such as illustrated and described in my previously filed application Serial No. 524,531, filed December 23, 1921, 80 the supporting frame work for the drawing mechanism being indicated at 1, on the top of which is located the platform 2 which not only carries the breaking and transferring mechanism forming the subject 85 matter of this invention but also the operating and driving mechanism (not shown) for actuating the drawing apparatus, all as clearly described in the aforesaid application.

The drawn sheet of glass is indicated at 3, passing upwardly through an opening 4 formed in the platform 2. Adjacent the opening 4 and the one side thereof is the cutting or scoring device indicated generally at 5. The cutting device used may be of any suitable construction and forms no part of the present invention, except in so far as it is embraced in the novel combination defined in the claims. That illustrated 100 in the drawings corresponds to the type shown in application Serial No. 524,531, above noted, and consists of a block 6 in which the cutter 7 is fixed, said block being mounted for reciprocation on cross pieces 8, 8'. Block 6 is attached to the upper limb of an endless chain 9 engaging sprocket wheels 10, 10', fixed to shafts suitably journaled at the opposite sides of the platform. The opposite end of the shaft to which 110

wheel 10 is fixed carries a pinion 11 which in turn is operatively connected through the sprocket chain 12 and the remaining gearing shown in the drawings to a reciprocating 5 rack bar 13 adapted to be actuated in properly timed relation to the remaining parts by the energization and deenergization of the solenoids 14, 14', all as clearly set forth in my previously filed application. This 10 cutting or scoring device while forming no part of the present invention, except in so far as it is embraced in the novel combination of associated elements, has been generally described so as to clearly indicate its relation 15 to the drawn sheet and the several parts forming the combined breaking and transferring device proper, the construction of which will now be set forth more in detail.

20 Located at the opposite sides of the platform 2 are the upstanding walls 15, 15', which serve as elongated standards in which to journal the several shafts, and upon which to mount the necessary supporting 25 brackets and bearings. Mounted in the members 15, 15' immediately above the cutting or scoring device 5 is a pair of guide rollers 16, 17, of corresponding size, the roller 16 being rendered adjustable in a 30 horizontal plane by means of a well known type of adjustable bearing illustrated at 18 in the drawings. The roller 17 is provided throughout its entire length with the alternately arranged enlarged portions 17' and 35 the reduced portions 17'', the peripheries of the enlarged portions 17' and the roller 16 being spaced apart so as to provide a guide slot therebetween, the guide slot being disposed in alignment with the normal vertical 40 path of travel of the drawn sheet 3. A breaking shaft 19 is likewise journaled in the members 15, 15', and is rendered vertically adjustable by means of the adjustable bearing indicated at 20, it being understood 45 that both ends of the roller 16 and of the shaft 19 are equipped with adjustable bearings of the character indicated. The shaft 19 is provided at its intermediate portion with the breaking cams 21, two being 50 preferably employed as clearly shown in Fig. 1. The shaft 19 is preferably of the same diameter as the roller 16, and is disposed in strict vertical alignment therewith, so as to lie immediately adjacent the upward 55 path of travel of the drawn sheet.

Journalled at one side of the guide rolls 16, 17, and in a plane corresponding to the axis of said rolls, is the shaft 22 of a rotatable carrier. The carrier consists of a plurality 60 of sets of radially extending arms 23, 23', three sets of said arms being used in the embodiment illustrated in the drawings. These radial arms are attached to the shaft 22 and are so mounted as to permit their extremitiess to project into close proximity

with the reduced portions 17'' of the guide roller 17, the ends of the arms passing through the spaces provided between the enlarged portions 17'. One face of the radial arms is provided adjacent its end 70 with a notch 24, immediately adjacent to which is affixed a transversely extending finger 25, the finger 25 being located intermediate the said notch and the shaft 22 and is slightly inclined towards the axis of the 75 carrier.

Disposed at the side of the rotatable carrier opposite to the guide rolls and breaking cams is an endless belt conveyor indicated generally by the reference numeral 26. 80 This conveyor is of a well known type, and consists of a series of shafts 27, 28, 29 and 30, suitably journaled in the supporting brackets or standards 31, lateral extensions of the members 15, 15', and a pair of arms 85 32, 32' projecting from one side of the members 15, 15'. The outer extremities of the arms 32, 32' are supported by the inclined braces 33, the lower ends of which may be suitably attached to the frame work 1. The 90 conveyor 26 consists of a plurality of spaced apart belt sections 34, 34', 34'', and 34''', the inner ends of which cooperate with supporting drums 35, 35', 35'' and 35''', respectively, each of these drums being mounted upon 95 a stub shaft corresponding to the shaft 27 located at the upper ends of individual supporting standards so as to leave a free space between the adjacent sections of the conveyor, through which spaces the radial arms 100 of the rotatable carrier are adapted to pass. (See particularly Fig. 1.)

Fixed to the extremities of the shafts for the rollers 16 and 17 are the intermeshing gears 36 and 37, said gears being of 105 similar size so as to rotate the rolls at a corresponding speed. Power is supplied to the guide rolls by means of a sprocket chain 38 and sprocket wheel 39, the chain 38 being driven from any suitable portion of the 110 actuating mechanism for the drawing apparatus, previously referred to. The shaft of the roller 17 at the end opposite to which the gear 37 is attached is supplied with a sprocket wheel 40 with which meshes the 115 sprocket chain 41, in turn meshing with a sprocket wheel 42 attached at one end of the shaft 30, thus serving to drive the conveyor 26.

Attached to one end of the shaft 19 is a 120 sprocket wheel 43, while at its opposite end is affixed the sprocket wheel 44. Suitably journalled at one end in a supporting bracket 45 and at their opposite ends in the member 15' is a pair of stub shafts 46, 47, 125 and attached to the stub shafts at an intermediate point are the gear wheels 48, 49, respectively. The stub shafts 46, 47 have also attached thereto the respective sprocket wheels 50 and 51. The shaft 22 has also 130

attached thereto at the end corresponding to the location of the sprocket wheels 50 and 51 a sprocket wheel 52. The sprocket wheels 44 and 50 are operatively connected by a sprocket chain 53 while the sprocket wheels 51 and 52 are likewise connected by a sprocket chain 54. The sprocket wheels 44, 50 and 51 are of a corresponding size, while the sprocket wheel 52 is twice the size 10 of the aforesaid sprocket wheels so as to establish a gear ratio of two to one between the shaft 19 and the shaft 52. The reason for this particular gear ratio is for the purpose of securing a breaking effect from the 15 breaking cams 21 twice during each revolution of the rotatable carrier. It is obvious that such gear ratio must be employed where each set of arms 23, 23' are arranged with the radial arms spaced 180° apart. It 20 will be obvious, however, that in case the angular spacing of these arms is varied, for instance by the employment of three radial arms spaced 120° instead of two arms spaced 180°, the gear ratio between the breaking 25 shaft and the rotatable carrier shaft will be correspondingly changed, that is, to a ratio of three to one. Power is supplied to the sprocket wheel 43 by means of the sprocket chain 55 for the purpose of driving 30 both the breaking shaft and the rotatable carrier, as just explained. The sprocket chain 55 like sprocket chain 38 is driven from any suitable connection with the actuating mechanism for the drawing 35 apparatus which may be suitably mounted at one side of the platform 2, as in my aforesaid application Serial No. 524,531.

In the operation of the invention, the drawn sheet 3 passes upwardly through the 40 opening 4 and through the space provided between the enlarged portions of the roll 17 and the roll 16, and the cutting or scoring device 5 is actuated periodically in order to score the drawn sheet transversely in a well 45 known manner. The sheet is guided during its upward movement by the guide slot formed between the two guide rolls, passing immediately adjacent the breaking shaft 19 during such upward movement. The parts 50 are so proportioned that when the sheet has reached a point to bring the line of scoring just above the axes of the guide rollers, the cams 21 will deflect the upper end of the sheet laterally, effecting a breaking off or 55 a snapping free of the section of glass along the previously scored line. The breaking action occurs at the time that the radial arms of the rotatable carrier occupy the full line position indicated in Fig. 4. Upon 60 breakage the resiliency of the glass sheet assisted by the tendency of the roller 17 to transfer the lower edge of the severed section 56 towards the right, results in depositing the severed section upon the extremity of the radial arm 23, 23', as the

case may be. Although the severed sheet, with the parts properly proportioned will remain upon the rotatable carrier until deposited upon the endless belt conveyor in a manner to be subsequently described, in 70 order to obviate accidental displacement, the notches 24 are provided into which the lower edges of the severed sections are adapted to settle, and the transversely extending fingers 25 are inclined slightly away from 75 the normal towards the axis of the carrier shaft.

After the severed section 56 has been deposited upon the rotatable carrier, the same is transported upon rotation of the carrier 80 from the position indicated by the full lines in Fig. 4 to the position indicated by the dotted lines in said figure or by the full lines in Fig. 3. Subsequent rotary movement in a clockwise direction, after reaching the position shown in Fig. 3, results in depositing the sheet upon the endless belt conveyor for delivery to the leers in the usual manner. The continued rotation of the radial arms is unobstructed by the conveyor 85 sections due to the free passage of the arms between the open spaces provided between the supporting drums 35 to 35'', as previously described.

During a single rotation of the shaft 22 95 each of the radial arms 23, 23', receives a severed section or pane in the manner set forth and delivers the same onto the endless conveyor. The breaking shaft 19 being geared to the shaft of the carrier in the 100 proper ratio, as set forth, the breaking mechanism and the carrier operate constantly in properly timed relation with each other.

Due to the mounting of the shaft for the 105 guide roll 16 in such manner that it may be adjusted in a horizontal plane provides means for accommodating the mechanism to drawn sheets of varying thicknesses, while the vertical adjustment for the breaking shaft 19 similarly provides means for adapting the parts to sheets or panes of different lengths, in an obvious manner.

It is thus seen that the invention provides 115 a very simple and compact mechanism for securing an effective breaking off of the severed sections or panes in a sheet glass drawing apparatus, one which is free of complicated parts and efficient in operation, one which is entirely automatic in its action and 120 adjustable for various sized sections or panes, and one which may be readily attached or adapted to use with sheet-glass drawing machines already in use.

I claim:

1. A breaking and transferring mechanism for sheet-glass drawing machines comprising an abutment adjacent the path of movement of the drawn sheet, means spaced from said abutment for deflecting the por- 120

tion of the sheet beyond the abutment away from said path whereby to break the same transversely to form detached sections, and a rotatable carrier disposed at one side of the abutment for receiving the detached sections, said carrier being mounted for free and complete revolution about its pivotal support.

2. A breaking and transferring mechanism for sheet-glass drawing machines comprising an abutment adjacent the path of movement of the drawn sheet, provided with a guide slot through which the drawn sheet passes, means spaced from said abutment for deflecting the portion of the sheet beyond the said slot away from said path whereby to snap the same transversely to form detached sections, and a rotatable carrier spaced from and at one side of the guide slot for receiving the detached sections, said carrier being mounted for free and complete revolution about its pivotal support.

3. A breaking and transferring mechanism for sheet-glass drawing machines comprising spaced rolls forming a guide slot therebetween through which the drawn sheet is adapted to pass, means spaced from the said rolls for periodically deflecting the portion of the sheet beyond the rolls away from its normal path of movement whereby to sever the sheet and form detached sections, and a rotatable carrier disposed at one side of the rolls having arms extending into close proximity thereto for receiving the said severed sections, said carrier being mounted for free and complete revolution about its pivotal support, and the axis of the carrier being spaced from the said slot a distance greater than the length of the said arms.

4. A breaking and transferring mechanism for sheet-glass drawing machines comprising spaced rolls forming a guide slot therebetween through which the drawn sheet is adapted to pass, a shaft mounted at one side of the path of travel of the drawn sheet beyond the guide slot, a cam on said shaft adapted to contact the drawn sheet to deflect the same away from the said path whereby to break the terminal portion of the drawn sheet to form detached sections, and a rotatable carrier having arms the extremities of which extend into close proximity to one of the said guide rolls for receiving the detached sections, said carrier being mounted for free and complete revolution about its pivotal support, and the axis of the carrier being spaced from the said slot a distance greater than the length of the said arms.

5. A breaking and transferring mechanism for sheet-glass drawing machines comprising a pair of spaced guide rolls forming a guide slot therebetween through which the drawn sheet is adapted to pass, one of said

rolls being provided with a series of alternately arranged enlarged and reduced portions, a shaft mounted at one side of the path of travel of the drawn sheet above the guide slot, a cam on the said shaft adapted to contact the drawn sheet to deflect the same away from its path of travel whereby to break the drawn sheet transversely to form detached sections, and a rotatable carrier having radial arms disposed at one side of said guide rolls, the extremities of said radial arms projecting between said enlarged portions and in close proximity to the said reduced portions for receiving the said detached sections.

6. A breaking and transferring mechanism for sheet-glass drawing machines comprising a pair of spaced guide rolls forming a guide slot therebetween through which the drawn sheet is adapted to pass, one of said rolls being provided with a series of alternately arranged enlarged and reduced portions, a shaft mounted at one side of the path of travel of the drawn sheet above the guide slot, a cam on the said shaft adapted to contact the drawn sheet to deflect the same away from its path of travel whereby to break the drawn sheet transversely to form detached sections, a rotatable carrier having radial arms disposed at one side of said guide rolls, the extremities of said radial arms projecting between said enlarged portions and in close proximity to the said reduced portions for receiving the said detached sections, and an endless conveyor disposed adjacent the carrier at the side opposite the said guide rolls, said conveyor consisting of a plurality of spaced apart sections, the said arms of the carrier being adapted to pass intermediate the said conveyor sections.

7. A breaking and transferring mechanism for sheet-glass drawing machines comprising spaced rolls forming a guide slot therebetween through which the drawn sheet is adapted to pass, a shaft mounted at one side of the path of travel of the drawn sheet beyond the guide slot, a cam on said shaft adapted to contact the drawn sheet to deflect the same away from said path whereby to break off the terminal portion of the drawn sheet to form detached sections, and a rotatable carrier having radial arms the extremities of which extend into close proximity to one of said guide rolls, and transverse fingers fixed to said arms adjacent the ends thereof.

8. A breaking and transferring mechanism for sheet-glass drawing machines comprising spaced rolls forming a guide slot therebetween through which the drawn sheet is adapted to pass, a shaft mounted at one side of the path of travel of the drawn sheet beyond the guide slot, a cam on said shaft adapted to contact the drawn sheet to

- deflect the same away from said path whereby to break off the terminal portion of the drawn sheet to form detached sections, and a rotatable carrier having radial 5 arms the extremities of which extend into close proximity to one of said guide rolls, each of said radial arms being provided with a notch adjacent its extremity and a transverse finger fixed thereto intermediate 10 said notch and the axis of the carrier, and an endless conveyor consisting of a plurality of spaced apart sections, the said arms of the carrier being adapted to pass between adjacent conveyor sections.
- 15 9. In combination with a sheet-glass drawing machine, a cutting or scoring device, a pair of spaced rolls mounted thereabove provided with a guide slot therebetween through which the drawn sheet is 20 adapted to pass, a breaking cam located above the said guide slot adapted to contact and deflect the drawn sheet away from its normal vertical path of movement whereby to sever the portion of the sheet 25 along the line at which it was previously scored, a rotating carrier having radial arms projecting into close proximity to the guide rolls, and a conveyor consisting of a plurality of spaced sections, the said radial 30 arms being adapted to pass intermediate adjacent sections of the said conveyor.
10. A breaking and transferring mechanism for sheet-glass drawing machines comprising a scoring device, a pair of spaced 35 guide rolls thereabove forming a guide slot
- therebetween through which the drawn sheet is adapted to pass, one of said rolls being provided with a series of alternately arranged enlarged and reduced portions, the remaining roll being adjustable to and from 40 the first named roll, a vertically adjustable shaft mounted above and at one side of the path of travel of the drawn sheet, a deflecting cam on said shaft adapted to contact and bend the said sheet laterally whereby to 45 break the same along the line at which it was previously scored to form detached sections, a rotatable carrier having radial arms extending between the said enlarged portions of the guide roll, each of said arms 50 being provided with a notch adjacent its extremity and with a transversely extending finger disposed at the inner edge of the notch, said transverse fingers being slightly inclined towards the axis of the carrier, and 55 an endless conveyor consisting of a plurality of spaced apart sections, the said radial arms of the carrier being adapted to pass intermediate adjacent sections.
11. The combination with a vertical glass 60 drawing machine and a carrier device extending laterally from the line of draw, of a transfer device in the form of a flat sided member mounted for rotation below the carrier and having projecting supporting 65 ledges at the ends of each of the sides of the member.

In testimony whereof, I sign my name.

THOMAS B. CAMPBELL, JR.
